PORTABLE HEATER

Eugene C. Briggs, Dayton, Ohio, assignor to Master Consolidated, Inc., Dayton, Ohio, a corporation of Ohio

Filed Nov. 26, 1963, Ser. No. 77,565

Term of patent 14 years

(Cl. D81—10)

FIG. 1 is a perspective view of a portable heater embodying my design;

FIG. 2 is a perspective view as seen from the opposite side of FIG. 1;

FIG. 3 is an end elevation thereof; and

FIG. 4 is a side elevation of the embodiment shown in FIG. 1, the differences residing in the handle members.

I claim:

The ornamental design for portable heater, substantially as shown and described.
